UNITED STATES PATENT OFFICE.

FRANCIS D. AMMEN, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,020,871.

Specification of Letter's Patent. Patented Mar. 19, 1912.

Application filed February 2, 1911. Serial No. 606,108.

To all whom it may concern:

Be it known that I, FRANCIS D. AMMEN, a citizen of the United States, residing in New York city, in the county of New York 5 and State of New York, have invented certain new and useful Improvements in Type-Writing Machines, of which the following is a specification.

This invention relates to typewriting machines, and particularly to such as are provided with a bichrome ribbon, and which are adapted to be used when desired to form stencils.

The invention is illustrated as applied to 15 a front strike typewriter, in which the ribbon is normally held slightly depressed below the striking face of the platen, and is raised automatically to come before the type when it strikes.

20 The object of the invention is to enable the ribbon to be actuated as suggested, and to provide a simple construction which will enable the ribbon to be "silenced", that is, held inoperative or inactive when desired, 25 so that the type may strike directly upon the wax sheet on the face of the platen.

In the accompanying drawings, Figure 1 is a plan, indicating certain parts of a front strike typewriter in dotted lines, and showing 30 the parts of the invention in full lines. Fig. 2 is a perspective, showing my improvement in full lines, as viewed from the rear, and indicating the universal bar in dotted lines in order to illustrate the manner of mounting my device in the machine. Fig. 3 is a perspective, showing a short portion of a way rod, showing the vibrator and ribbon lever, and also showing the construction of the ribbon lever. Fig. 4 is a 35 perspective, showing the actuator which moves the ribbon lever, and indicating the manner in which it is mounted and secured in the universal bar. Fig. 5 is a perspective, showing the cam by means of which the actuator is controlled. Fig. 6 is a rear elevation of the parts of my device, showing the link which moves the cam broken away, and showing the parts immediately contiguous to my improvement in dotted lines. Fig. 7 40

45 is a side elevation of the parts of my invention, a way rod being shown in cross section, and the universal bar and adjacent parts being shown in dotted outline. This view shows the machine for writing in red and 50 on the lower band of the bichrome ribbon.

Fig. 8 is a view similar to Fig. 7, but showing the vibrator broken away, and illustrating the parts in the silenced position, so that the vibrator will not be actuated to raise the ribbon enabling the type to strike directly upon the stencil sheet.

1 represents a typewriter frame of the front strike type, and in the rear portion of this frame a universal bar 2 is mounted in any usual manner, the rear end thereof being supported on a suitable rocker 3, and the forward end being disposed adjacent to a segment 4 in such a position that the universal bar will be moved rearwardly during the type action.

70 In applying my invention, I attach on the rear face of the way rod 5 of the typewriter an angle bracket 6, in the form of a downwardly and rearwardly inclining arm to which the ribbon lever 7 is pivotally attached, as shown, said lever having a curved lower arm 8 to which the lower end of the vibrator 9 is pivotally attached, as indicated. The upper end of the vibrator carries the ribbon 10 in the usual manner.

75 I provide the lever 7 with an upwardly extending arm 11 having an elongated vertical slot 12 formed therein. The material forming the rear side of the lever at this point is offset rearwardly in a loop to form 80 a gap or throat 13 extending rearwardly from the slot 12. Just to the rear of the lever 7 on the universal bar 2, I attach rigidly a guide sleeve 14, a portion of which extends below the universal bar, as indicated. In this sleeve, from the upper end 85 thereof, there is received a flat shank 15 on an actuator 16, the upper end of the actuator having two forks 17 between which a wrist pin 18 is mounted, as indicated, and this wrist pin 18 lies in the aforesaid slot 12, 90 as shown. On the rear face of the shank 15 I provide a rearwardly projecting pin 19.

95 It should be understood that when the universal bar is moved the actuator 16 may 100 rock the lever 7 so as to move the vibrator 9. In order to control or adjust the position of the actuator, on the rear face of the guide sleeve 14, I provide a cam 20 which is preferably in the form of a slide or sliding 105 plate, the body of said plate being disposed in a vertical plane and having an inclined slot 21 which receives the aforesaid pin 19, as indicated. The lower portion of the plate is bent laterally so as to form a guide-foot 110.

22, and this guide-foot has two elongated alining slots 23 through which guide-screws pass, said guide screws being seated in the universal bar 2, as shown.

5 In this construction, it should be understood that when the cam is in the position shown in Fig. 2, the actuator is in its extreme depressed position, and at this time the wrist pin 18 is located in the lower end of 10 the slot 12. When the universal bar moves rearwardly by the type action, the wrist pin 18 will have a rearward or lateral movement, and rocks the arm 11 of the lever 7, elevating the vibrator 9 sufficiently to bring the 15 lower band or red band of the bichrome ribbon opposite the striking point on the platen. If the cam is thrown to an extreme position toward the left side of the machine, the slot 21 will move the pin 19 upwardly, and this 20 raises the actuator so that the wrist moves into the upper end of the slot 12. When this occurs the movement of the universal bar will actuate the lever 7, but will give the ribbon just sufficient movement to bring the 25 upper or black band opposite the striking point.

In the mid-position of the cam, the wrist pin 18 of the actuator will lie opposite to the gap or throat 13 of the slot 12, so that when 30 the universal bar is actuated, the actuator wrist pin 18 moves out into the gap or throat 13 without actuating the lever 7. The position of the cam may be controlled by a link 35 which is attached to the cam loosely by a pivot screw 26^a, and extends over toward the right of the machine where it is pivotally connected with a rigid arm 26 extending upwardly from a rock shaft 27. This rock shaft is of the usual construction and 40 extends horizontally toward the forward side of the machine where it is provided with a rigid cross arm 28 having keys 29, 30, the former of which should be depressed to adapt the mechanism for writing black, and 45 the latter of which is depressed to adapt the machine for writing red. This cross arm 28 is normally held in mid-position by means of a suitable controlling device 31.

The ribbon 10 passes from a guide spool 50 32 through the upper end of the vibrator to a similar guide spool on the opposite side of the machine.

In Fig. 8 is illustrated the type bar 33 striking the platen 34, and indicating how 55 the heel 35 of the type bar forces the universal bar 2 rearwardly in the usual manner. The rearward movement of the universal bar however does not move the lever for the reason that the wrist 18 moves into 60 the gap 13, as shown.

Having thus described my invention, I claim:

1. In a typewriting machine, in combination, a ribbon holder, a lever pivoted there- 65 to, an actuator, a universal bar, a guide for

said actuator on said universal bar, a connection between said lever and said actuator normally affording means at one point for moving said lever when said actuator moves, and means for holding said actuator at another point in said guide at which said connection is inoperative.

2. In a typewriting machine having a universal bar, a ribbon lever pivotally mounted adjacent thereto and having an actuating arm, the combination of a vibrator attached to said lever, an actuator guided on said universal bar, said actuator having a free connection with said arm, and being adapted to rock said lever by a lateral movement, said arm having a form at one point permitting the independent lateral movement of said actuator when in a mid position, and means for controlling the position of said actuator.

3. In a typewriting machine, in combination, a vibrator, a lever connected therewith for actuating the same, a universal bar, said lever having an elongated slot therein, with a laterally projecting gap at the side thereof, an actuator mounted on said universal bar and adapted to be raised or lowered thereupon, said actuator having a wrist running in said slot, said wrist affording means for normally moving said lever, said gap affording means for permitting the movement of said wrist without actuating said lever.

4. In a typewriting machine, in combination, a member adapted to raise and lower the ribbon, a universal bar actuated by the type bars, an actuator adjustably mounted on said universal bar, and a connection between said actuator and said member comprising a pin on one constantly riding in a slot on the other, said slot of said connection having a lateral extension in which said pin may ride idly.

5. In a typewriting machine, in combination, a vibrator, a lever pivotally connected therewith and having an arm with a slot therein, a universal bar, an actuator on said bar, said actuator having a pin running in said slot, and said slot having a laterally disposed gap which may receive said pin, enabling said actuator to move with said universal bar without actuating said lever, and a cam for shifting said actuator up and down on said universal bar.

6. In a typewriting machine, the combination with a reciprocating universal bar, of a sleeve thereon, a ribbon vibrator, an actuator constantly engaging said vibrator, and a key operated member to positively move and hold said actuator in said sleeve to vary the throw of said vibrator.

7. In a typewriting machine, the combination with a reciprocating universal bar, of a sleeve thereon, a ribbon vibrator comprising a slot, an actuator carrying a pin con- 1

stantly engaging the slot in said vibrator, and a key controlled double cam moving said actuator in said sleeve to vary the throw of said vibrator.

5. In a typewriting machine, the combination with a pivoted ribbon vibrating lever, of a pin riding in an opening therein, a universal bar actuating said pin to vibrate said lever, so that when adjacent one 10 end of said opening it brings one edge of said ribbon to the printing point, and when adjacent the other end of said slot it brings the other edge of said ribbon to the printing point, and a break in the wall of said opening forming an aperture in which said pin 15 may ride idly.

9. In a typewriting machine, the combination with a pivoted ribbon vibrating lever, of a pin riding in an opening therein, a universal bar actuating said pin to vibrate 20 said lever, so that when adjacent one end of said opening it brings one edge of said ribbon to the printing point, and when adjacent the other end of said slot it brings the other edge of said ribbon to the printing 25 point, and a break in the wall of said opening forming an aperture between said ends in which said pin may ride idly.
